UNITED STATES PATENT OFFICE

156,079

DESIGN FOR AN ANTIUME DEVICE OR SIMILAR ARTICLE

Frank J. Doyle, Bronxville, N. Y.

Application February 25, 1949, Serial No. 1,085

Term of patent 7 years

(Cl. D26—1)

To all whom it may concern:

Be it known that I, Frank J. Doyle, a citizen of the United States, residing at Bronxville, in the county of Westchester, and State of New York, have invented a new, original, and ornamental Design for an Antilime Device or Similar Article, of which the following is a specification, reference being had to the accompanying drawing, forming part thereof.

Figure 1 is a view in perspective of an antilime device or similar article embodying my new design;

Figure 2 is a view in top plan; and

Figure 3 is a bottom plan view thereof.

I claim:

The ornamental design for an antilime device or similar article, as shown.

FRANK J. DOYLE.
